UNITED STATES PATENT OFFICE.

ALONZO WINSTEAD, OF SHARPSBURG, NORTH CAROLINA.

ANTI-RAIL-SPREADING DEVICE.

1,168,449.

Specification of Letters Patent.

Patented Jan. 18, 1916.

Application filed May 14, 1915. Serial No. 28,106.

To all whom it may concern:

Be it known that I, ALONZO WINSTEAD, a citizen of the United States, residing at Sharpsburg, in the county of Nash and State 5 of North Carolina, have invented certain new and useful Improvements in Anti-Rail-Spreading Devices; and I do hereby declare the following to be a full, clear, and exact description of the invention, such as will 10 enable others skilled in the art to which it appertains to make and use the same.

The invention relates to an anti-rail spreading device.

The object of the present invention is to 15 improve the construction of devices for preventing the spreading of rails and to provide a simple, practical, and inexpensive device adapted to be readily applied to a track and capable of firmly holding the rails at 20 the proper gage and of effectively preventing the same from moving either inwardly or outwardly whereby accidents incident to the spreading of the rails will be eliminated.

With these and other objects in view the 25 invention consists in the construction and novel combination and arrangement of parts hereinafter fully described, illustrated in the accompanying drawings and pointed out 30 in the claims hereto appended, it being understood that various changes in the form, proportion and minor details of construction may be resorted to without departing from the spirit or sacrificing any of the ad- 35 vantages of the invention.

In the drawing Figure 1 is a plan view partly in section of an anti-rail spreading device constructed in accordance with this 40 invention, Fig. 2 is a vertical sectional view of one end of the device on the line 2—2 of Fig. 1, Fig. 3 is a similar view on the line 3—3 of Fig. 1, Fig. 4 is a detail transverse sectional view illustrating another form of the invention, Fig. 5 is a detail sectional 45 view on the line 5—5 of Fig. 1.

Like numerals of reference designate corresponding parts in all the figures of the drawing.

In the accompanying drawing in which is 50 illustrated the preferred embodiment of the invention, the anti-rail spreading device comprises in its construction a gage bar or rod 1 equipped at its ends with upper and lower rail engaging jaws 2 and 3 arranged 55 to embrace a rail 4 at the upper and lower

faces of the inner bottom flange 5 thereof as clearly shown in Figs. 2 and 4 of the drawings. The upper jaw is provided with an inclined lower face 6 to fit against the bottom flange of the rail and a vertical edge 60 7 for engaging the web 8 of the rail and the lower jaw 3 which is substantially straight may extend entirely across the bottom of the rail but the lower jaw 3 is preferably of the same length as the upper jaw 2 so as to terminate in the vertical plane of the end of the said upper jaw. The gage bar or rod is designed to be constructed of tubular metal and the upper and lower rail engaging jaws which form a stop for limiting the inward 65 movement of the rail may be formed integral with the gage bar or rod 1 as shown in Fig. 4 or they may be carried by an adjustable tubular section 9 provided with interior screw threads 10 and engaging a threaded 70 portion 11 of the rod or bar 1. This construction enables the gage rod or bar 1 to be varied in length to enable the device to be applied to roads of different gages, and after the end sections 9 have been properly 75 adjusted to suit the gage of the road they are locked in their adjustment by nuts 12, arranged on the threaded terminal portions of the bar or rod 1 and engaging the inner 80 ends of the tubular sections 9. The upper 85 jaw 2 is extended upwardly along the web portion of the rail to brace the latter and prevent the same from rocking inwardly but the interlocking of the bottom flange of the rail with the jaws of the gage rod or bar 90 will effectively prevent any rocking movement of the rails.

The rails are securely held against outward movement to prevent spreading by a pair of adjustable tie rods 13 provided at 95 their outer ends with hooked-shaped engaging portions 14 preferably flattened as shown and extending beneath the rail and upwardly and inwardly at the outer side thereof and engaging and embracing the outer 100 bottom flange of the rail as clearly illustrated in Fig. 3 of the drawing. The inner portions 15 of the tie rods are threaded and are engaged by a turn buckle 16 which is adapted to be rotated to move the tie rods 105 inwardly and outwardly. The threads of the inner portions 15 are right and left hand and the threads of the turnbuckle are correspondingly made so that the rotary movement of the turn buckle will simulta- 110

neously move the tie rods inwardly or outwardly according to the direction of the rotation of the turn buckle.

The tie rods are slideable through openings 5 17 in links 18 which are also provided with openings 19 through which the gage bar or rod passes. The openings 18 and 19 are located at the ends of the links and the latter are mounted on the gage rod or bar between 10 spaced collars 20 suitably fixed to the said gage rod or bar and adapted to prevent movement of the links longitudinally of the said bar or rod 1 and at the same time permit the links to swing upwardly and downwardly to enable the tie rods 13 to be engaged with and disengaged from the rails. When the engaging ends of the tie rods are moved outwardly beyond the rails, the links will permit the tie rods to drop downwardly 15 and they also permit the tie rods to be raised to a position for engaging the rails. When the device is in position the rails are firmly engaged at their inner and outer sides and they are effectively prevented from spreading or 20 moving inwardly so that the proper gage of the rails is maintained.

In practice the anti-rail spreading device will be arranged at intervals of about eight feet more or less and as the device can be 30 manufactured in the neighborhood of about fifty cents it will be apparent that it is exceedingly inexpensive compared with the safety assured by the use of a device on a road.

35. What is claimed is:—

1. An anti-rail spreading device including a gage bar, of a length to extend across a track and provided with terminal means for engaging the rails at one side thereof, 40 pivoted arms located between the rails and extending from and carried by the gage bar, and means carried by the said arms for engaging the rails at the other side thereof, said arms permitting the last mentioned 45 means to swing into and out of position for engaging the said rails.

Copies of this patent may be obtained for five cents each, by addressing the "Commissioner of Patents, Washington, D. C."

2. An anti-rail spreading device including a gage bar or rod provided with means for engaging the rails at the inner sides thereof to form stops for preventing inward movement of the rails, links or arms extending from the gage bar or rod, tie rods slidably connected with the links or arms and provided at their outer ends with means for engaging the rails at the outer sides thereof to prevent the rails from spreading and means for adjustably connecting the inner portions of the tie rods. 50

3. An anti-rail spreading device of the class described including a gage bar or rod 60 provided with means for engaging the rails at the inner sides thereof to prevent the rails from moving inwardly, links pivotally connected with the gage bar or rod, and arranged at right angles thereto and provided with openings, tie rods slideable in the openings and provided at their outer ends with means for engaging the rails at the outer side thereof and a device adjustably connecting the inner portions of the tie rods 65 and adapted to move the same inwardly and outwardly. 70

4. A device of the class described including a gage bar or rod having threaded terminals, arms extending from the gage bar at 75 the inner ends of the said threaded terminals, threaded sections engaging the threaded terminals of the gage bar or rod and provided with means for engaging the rails of a track at one side of the said rails and 80 means carried by the said arms for engaging the rails at the other side thereof, said arms permitting the last mentioned means to swing into and out of position for engaging the rails. 85

In testimony whereof I affix my signature in presence of two witnesses.

ALONZO WINSTEAD.
